DESIGN FOR A HAND GRENADE

Jesus R. Montano, Earlimart, Calif.

Application July 15, 1942, Serial No. 107,542

Term of patent 14 years

To all whom it may concern:

Be it known that I, Jesus R. Montano, a citizen of Mexico, residing at Earlimart, in the county of Tulare and State of California, have invented a new, original, and ornamental Design for a Hand Grenade, of which the following is a specification, reference being had to the accompanying drawing, forming part thereof.

I claim:

The ornamental design for a hand grenade, as shown.

JESUS R. MONTANO.
